UNITED STATES PATENT OFFICE

ARTHUR SAMUEL NEWMAN, OF HIGHGATE, ENGLAND, ASSIGNOR TO KODAK, LIMITED,
OF HOLBORN, LONDON, ENGLAND

CINEMATOGRAPH APPARATUS

Application filed May 28, 1929, Serial No. 366,719, and in Great Britain June 1, 1928.

The invention relates to that kind of cinematograph apparatus in which the main shaft has a crank mounted thereon, the pin of which gives motion to a block sliding 5 within a slot in a lever, said lever being mounted upon the driven shaft, which latter gives motion to the mechanism for driving the film. In such apparatus it has been proposed to employ means to move the driving shaft and the driven shaft more and less eccentric with relation to each other for the purpose of varying the ratio of period of rest of the film to that of the feeding movement thereof.

15 The object of the present invention is to provide improved means for varying the amount of eccentricity between the driving shaft and the driven shaft and, further, to combine with such driving mechanism improved means for driving the film.

20 According to the present invention the driving shaft is mounted in a bearing in one side of a casing and the driven shaft is mounted in a bearing in the opposite side 25 of the casing, and means are provided for allowing one side of the casing to be moved with respect to the other side of the casing and for fixing the two parts of the casing in any desired relationship to each other.

30 The driven shaft is provided with a crank, the crank pin of which gives motion to one end of a lever which is pivoted intermediate of its ends to a swinging shaft and the driving claws are preferably pivoted to the 35 said lever so that they may swing independently of each other. For this purpose a bar forming part of the said lever is provided with a cross bar having pins acting as stops for the two claw levers, which latter are normally retained against the stops by means of a suitable spring.

40 The parts are preferably so arranged that the straighter side of the D shaped path traversed by the claws is closer to the path 45 of the film at the entering end than at the leaving end. From this it results that the claws commence to drive the film before they have entered fully into the perforations. As they continue to drive the film 50 the springs cause the claws to fully enter

the perforations, and the claws rock upon the said rocking shaft and slowly leave the stops carried by the main lever.

At the end of the driving stroke of the main lever, when the crank pin of the secondary shaft, the secondary shaft and the axis of the swinging shaft are in alignment, the stops on the ends of the said cross bar again come into contact with the claw levers and move them slowly out of the perforations while the film is stationary.

One side of the casing, preferably that side carrying the bearing for the driving shaft, is provided with a flange having apertures therein adapted to receive binding screws, and the other side of the casing carrying the bearing for the driven shaft is likewise provided with a flange provided with slots adapted to guide this last mentioned part of the casing with respect to the said binding screws, and said binding screws are employed in combination with the slots to fix the two parts of the casing with respect to each other.

55 The invention is illustrated in the accompanying drawings in which:

Fig. 1 is a front elevation of a projecting apparatus partly broken away.

Fig. 2 is a side elevation of the same, partly broken away, and Fig. 3 is a section 60 through the casing containing the driving mechanism and also partly broken away.

Fig. 4 shows diagrammatically, on an enlarged scale, a path through which the claws would pass if unmodified by the film support.

65 Fig. 2 is the driving shaft which is provided with a crank 3 having a driving pin 4 thereon. Upon the driving pin 4 is mounted a block 5, a part 6 of which is formed to slide within a slotted crank 7 carried by a driven shaft 8.

The inner ends of the driving shaft 2 and of the driven shaft 8 are mounted within a casing 9 having a flange 10 against which 70 fits a closing plate 11.

75 It will be noticed from Fig. 3 that the driven shaft 8 is mounted on and is concentric with respect to the casing 9 and that the driving shaft 2 is mounted in the plate 100

11 and is eccentric to such casing. The flange 10 of the casing is formed with slots 12 through which pass binding screws 13 entering the closing plate 11. By releasing 5 the screws 13 the casing 9 and the plate 11 may be moved with respect to each other, thereby causing the driving shaft 2 to be more or less eccentric with respect to the driven shaft 8. When the shafts 2 and 8 10 are moved farther apart the change becomes more rapid.

The casing is preferably made oil tight. The driven shaft 8 is provided with a crank 14 which is pivoted at its outer end at 15 15 to the main lever 16 which latter is pivoted intermediate of its ends upon a swinging shaft 17 which projects across the film. The swinging shaft 17 is connected by arms 18 to a rocking shaft 19 mounted in bearings 20 carried by the base plate 210. The swinging shaft 17, arms 18 and rocking shaft 19 are all preferably made tubular, thereby reducing the weight of these reciprocating parts.

25 The rocking shaft 19 is located entirely on one side of the path of the film and it is of such a length and the bearings 20 are at such a distance apart to ensure that there is no shake on the swinging shaft 17, although this latter is quite free to swing with the rocking shaft 19.

The main lever is made in several parts; the part 16 being rigidly fixed to a portion 21 which is pivoted on the swinging shaft 17 35 and has connected to it one end of a sleeve 22 which is fixed at its other end to a central bar 23 upon the upper end of which is fixed a cross bar 24.

Surrounding the sleeve 22 is an outer 40 sleeve 25 to which is fixed one of the claw levers 26. The other claw lever 26 is fixed to a sleeve 27 mounted on the swinging shaft 17. The claw levers 26 are normally retained against stops 28, carried at both ends 45 of the cross bar 24, by means of a leaf spring 29 which is perforated about its centre and is placed over a screw 30 carried by the bar 23.

One end of the spring 29 bears upon the 50 end of the sleeve 22 mounted on the shaft 17, and the other end of the spring 29 bears upon the centre of a cross bar 31, the ends of which bear upon the claw levers 26, carrying the claws 32.

55 A nut 33 upon the screw 30 enables the pressure of the spring 29 to be adjusted. The spring 29 and the bar 31 may be readily retained in position with respect to each other and with relation to the claw levers 26 60 by means of pins 34 on the claw levers 26 passing through holes in the end of the bar 31. The bar 31 may carry a pin 35 which passes through the end of the spring 29.

The straighter side of the D shaped path 65 traversed by the claws is closer to the path

of the film at the entering end than at the leaving end, as shown in Fig. 4. From this it results that the claws 32 commence to drive the film before they have entered fully into the perforations. As they continue to drive the film the spring 29 causes the claws 32 to fully enter the perforations and to be supported by the film, and the claws rock upon the said swinging shaft 17 and slowly leave the stops 28 carried by the part 23 of 70 the main lever.

At the end of the driving stroke of the main lever when the crank pin 15, the crank 14, the driven shaft 8 and the swinging shaft 17 are in alignment, the stops 28 on the ends 80 of the cross bar 24 again come into contact with the claw levers 26 and move them slowly out of the perforations while the film is stationary.

It will be noticed from Fig. 2 that the 85 claws are set at such an angle as to be practically a tangent to a circle struck from the axis of the swinging shaft 17, that they enter and leave the perforations when the main lever is merely rocking on the swinging 90 shaft 17, without causing any motion of the film, and that they only move the film when the main lever is being drawn downwardly by the crank pin 15 driving the same.

The gate 36 is spring pressed as usual towards the rear plate 37, the two parts 36 and 37 being retained in relation to each other by any suitable means, not shown. 38 is the aperture in the gate.

As there is no novelty in the gate the 100 whole of the gate is not shown, and the spring for retaining the parts 36 and 37 in contact with each other or in contact with the film 39 (shown only in Figs. 2 and 4) 105 is likewise not shown.

In Fig. 4 the broken line 40 denotes the path that the claws would take if it were not modified by the support of the film.

Although the drawings show a projecting apparatus the mechanism is equally suitable for use in a cinematograph camera.

What I claim as my invention is:—

1. In means for driving cinematograph apparatus the combination of a driving shaft, a crank on said main shaft, a driving pin on said crank, a slotted crank driven by the crank pin, a driven shaft on which the slotted crank is mounted, a casing having a closing plate, a bearing on said closing plate in which the driving shaft is mounted, a bearing on the casing in which the driven shaft is mounted, means provided on the closing plate and on the casing to enable these latter to slide and to be fixed with respect to each other, a crank on the driven shaft, a lever one end of which is driven by the said last mentioned crank, a swinging shaft on which the said lever is pivoted intermediate of its ends, and claws 115 120 125 130 135

moved by the other end of said lever, substantially as set forth.

2. In means for driving cinematograph apparatus the combination of a driving shaft, a crank on said main shaft, a driving pin on said crank, a slotted crank driven by the crank pin, a driven shaft on which the slotted crank is mounted, a casing having a closing plate, a bearing on said closing plate in which the driving shaft is mounted, a bearing on the casing in which the driven shaft is mounted, means provided on the closing plate and on the casing to enable these latter to slide and to be fixed with respect to each other, a crank on the driven shaft, a lever one end of which is driven by the last mentioned crank, a swinging shaft on which the said lever is pivoted intermediate of its ends, a rocking shaft, arms connecting the rocking shaft to the said swinging shaft, and claws moved by the other end of said lever, substantially as set forth.

3. In means for driving cinematograph apparatus the combination of a driving shaft, a crank on said main shaft, a driving pin on said crank, a slotted crank driven by the crank pin, a driven shaft on which the slotted crank is mounted, a casing having a closing plate, a slotted flange on the casing, screws passing through the slotted flange and entering the closing plate, a bearing on said closing plate in which the driving shaft is mounted, a bearing on the casing in which the driven shaft is mounted, a crank on the driven shaft, a lever one end of which is driven by the last mentioned crank, a swinging shaft on which the said lever is pivoted intermediate of its ends, and claws moved by the other end of said lever, substantially as set forth.

4. In means for driving cinematograph apparatus the combination of a driving shaft, a crank on said main shaft, a driving pin on said crank, a slotted crank driven by the crank pin, a driven shaft on which the slotted crank is mounted, a casing having a closing plate, a slotted flange on the casing, screws passing through the slotted flange and entering the closing plate, a bearing on said closing plate in which the driving shaft is mounted, a bearing on the casing in which the driven shaft is mounted, a crank on the driven shaft, a lever one end of which is driven by the last mentioned crank, a swinging shaft on which the said lever is pivoted intermediate of its ends, and claws separately pivoted on the swinging shaft and moved by the other end of said lever, substantially as set forth.

5. In means for driving cinematograph apparatus the combination of a driving shaft, a crank on said main shaft, a driving pin on said crank, a slotted crank driven by the driving pin, a driven shaft on which the slotted crank is mounted, a casing having a

closing plate, a bearing on said closing plate in which the driving shaft is mounted, a bearing on the casing in which the driven shaft is mounted, means provided on the closing plate and on the casing to enable these latter to slide and to be fixed with respect to each other, a crank on the driven shaft, a lever one end of which is driven by the last mentioned crank, a swinging shaft on which the said lever is pivoted intermediate of its ends, a rocking shaft, arms connecting the rocking shaft to the said swinging shaft, and claws moved by the other end of said lever, substantially as set forth.

6. In means for driving cinematograph apparatus the combination of a driving shaft, a crank on said main shaft, a driving pin on said crank, a slotted crank driven by the driving pin, a driven shaft on which the slotted crank is mounted, a casing having a closing plate, a bearing on said closing plate in which the driving shaft is mounted, a bearing on the casing in which the driven shaft is mounted, means provided on the closing plate and on the casing to enable these latter to slide and to be fixed with respect to each other, a crank on the driven shaft, a lever one end of which is driven by the last mentioned crank, a swinging shaft on which the said lever is pivoted intermediate of its ends, a rocking shaft, arms connecting the rocking shaft to the said swinging shaft, and claws separately pivoted on the swinging shaft and moved by the other end of said lever, substantially as set forth.

7. In means for driving cinematograph apparatus the combination of a driving shaft, a crank on said main shaft, a driving pin on said crank, a slotted crank driven by the crank pin, a driven shaft on which the slotted crank is mounted, a casing having a closing plate, a bearing on said closing plate in which the driving shaft is mounted, a bearing on the casing in which the driven shaft is mounted, means provided on the closing plate and on the casing to enable these latter to slide and to be fixed with respect to each other, a crank on the driven shaft, a lever one end of which is driven by the last mentioned crank, a swinging shaft on which the said lever is pivoted intermediate of its ends, a cross bar on the other end of said lever and claw levers pivoted on the swinging shaft and controlled by said cross bar, substantially as set forth.

8. In means for driving cinematograph apparatus the combination of a driving shaft, a crank on said main shaft, a driving pin on said crank, a slotted crank driven by the crank pin, a driven shaft on which the slotted crank is mounted, a casing having a closing plate, a bearing on said closing plate in which the driving shaft is mounted, a bearing on the casing in which the driven shaft is mounted, means provided on the

closing plate and on the casing to enable these latter to slide and to be fixed with respect to each other, a crank on the driven shaft, a lever one end of which is driven by 5 the said last mentioned crank, a swinging shaft on which the said lever is pivoted intermediate of its ends, a cross bar on the other end of said lever, stops on said cross bar, claw levers pivoted on the swinging 10 shaft and a spring to normally retain the claw levers in contact with said stops, substantially as set forth.

9. In means for driving cinematograph apparatus the combination of a driving 15 shaft, a crank on said main shaft, a driving pin on said crank, a slotted crank driven by the crank pin, a driven shaft on which the slotted crank is mounted, a casing having a closing plate, a bearing on said closing plate 20 in which the driving shaft is mounted, a bearing on the casing in which the driven shaft is mounted, means provided on the closing plate and on the casing to enable these latter to slide and to be fixed with respect to each other, a crank on the driven 25 shaft, a lever one end of which is driven by the said last mentioned crank, a swinging shaft on which the said lever is pivoted intermediate of its ends, a cross bar on the 30 other end of said lever, stops on said cross bar, claw levers pivoted on the swinging shaft, a second cross bar bearing at its ends upon the claw levers and a spring bearing upon the last mentioned cross bar to normally 35 retain the claw levers in contact with said stops, substantially as set forth.

10. In means for driving cinematograph apparatus the combination of a driving shaft, a crank on said main shaft, a driving 40 pin on said crank, a slotted crank driven by the crank pin, a driven shaft on which the slotted crank is mounted, a casing having a closing plate, a slotted flange on the casing, screws passing through the slotted flange 45 and entering the closing plate, a bearing on said closing plate in which the driving shaft is mounted, a bearing on the casing in which the driven shaft is mounted, a crank on the driven shaft, a lever one end of which is 50 driven by the last mentioned crank, a swinging shaft on which the said lever is pivoted intermediate of its ends, a cross bar on the other end of said lever and claw levers pivoted on the swinging shaft and controlled 55 by said cross bar, substantially as set forth.

11. In means for driving cinematograph apparatus the combination of a driving shaft, a crank on said main shaft, a driving pin on said crank, a slotted crank driven by 60 the crank pin, a driven shaft on which the slotted crank is mounted, a casing having a closing plate, a slotted flange on the casing, screws passing through the slotted flange and entering the closing plate, a 65 bearing on said closing plate in which the

driving shaft is mounted, a bearing on the casing in which the driven shaft is mounted, a crank on the driven shaft, a lever one end of which is driven by the last mentioned crank, a swinging shaft on which the said 70 lever is pivoted intermediate of its ends, a cross bar on the other end of said lever, stops on said cross bar, claw levers pivoted on the swinging shaft and a spring to normally retain the claw levers in contact with 75 said stops, substantially as set forth.

12. In means for driving cinematograph apparatus the combination of a driving shaft, a crank on said main shaft, a driving pin on said crank, a slotted crank driven by the crank pin, a driven shaft on which the slotted crank is mounted, a casing having a closing plate, a slotted flange on the casing, screws passing through the slotted flange and entering the closing plate, a bearing on said closing plate in which the driving shaft is mounted, a bearing on the casing in which the driven shaft is mounted, a crank on the driven shaft, a lever one end of which is driven by the last mentioned crank, a swinging shaft on which the said 80 lever is pivoted intermediate of its ends, a cross bar on the other end of said lever, stops on said cross bar, claw levers pivoted on the swinging shaft, a second cross bar 85 bearing at its ends upon the claw levers and a spring bearing upon the last mentioned cross bar to normally retain the claw levers in contact with said stops, substantially as 90 set forth.

100 In witness whereof I have hereunto set my hand.

Signed at London, England, this 13th day of May, 1929.

ARTHUR SAMUEL NEWMAN.
